UNITED STATES PATENT OFFICE.

JOHN W. HUGHES, OF MACON, GEORGIA.

COMBINATION OR CONVERTIBLE ARTICLE OF FURNITURE.

No. 825,540.

Specification of Letters Patent.

Patented July 10, 1906.

Application filed December 27, 1905, Serial No. 293,437.

To all whom it may concern:

Be it known that I, JOHN W. HUGHES, a citizen of the United States, residing at Ma-
5 con, in the county of Bibb and State of Georgia, have invented certain new and useful Improvements in a Combination or Con-
vertible Article of Furniture, of which the following is a specification.

My invention relates to a combination or convertible article of furniture designed to serve efficiently as a crib and also as an arched settee and capable of being folded into small compass for storage when not in use or for shipment.

15 To the end stated the invention consists in an article of furniture constructed and arranged and possessing the advantages hereinafter set forth and claimed, reference being made to the accompanying drawings, in
20 which—

Figure 1 is a perspective view illustrating the article with its parts disposed for use as a crib with head, foot, and side pieces. Fig. 2 is a similar view with the parts disposed for use as a settee. Fig. 3 is a perspective view illustrating a type of cushion suitable for serving as a mattress for the article of furniture when used as a crib or a cushion when used as a settee. Fig. 4 is a detail illustrating the manner in which the extension of the cushion may be disposed under the hinged side of the crib when the latter is folded over or under the seat portion of the settee and held between said crib hinged side and the seat portion of the article to hold the cushion in place. Fig. 5 is an elevation showing the several members of the article folded or nested together for compactness in storage or shipment, and Fig. 6 is a top plan view of the article when the parts are packed together.

In the said drawings the reference-numeral 1 designates the permanent back, which when the article is used as a crib serves as one side wall thereof and which constitutes the base 45 or frame of the article. As shown, it is provided with end posts 2, the lower extremities of which constitute supporting legs or feet 3. The end posts extend forwardly, as shown at 4, from the plane of the back 1 for a purpose 50 hereinafter referred to. Hinged to the forward edges of the end posts are sections 5 and 6, provided at their forward ends with extensions which constitute legs or feet 7, that co-operate with the feet 3 to support the article 55 when used as a crib or settee. Said sections are provided upon their inner faces with rails

8, that serve to receive and support the bottom 9 both when the article is in use as a crib or as a settee. This bottom is hinged or pivoted to the end post 2 within the field of the 60 sections 5 and 6, so that it may be folded up in line with the back 1 when the members of the article are folded together for shipment or may be swung down against the rails when the article is in use. This bottom 9 constitutes the bed crib-bottom when the article is in use as such and consists of end bars 10, to which are secured a series of longitudinal springs 11. The springs may be of any suitable type and secured in any suitable manner. As shown, they consist of strip-springs attached by screws at their opposite ends to the end bars 10. This element so constructed serves efficiently as a bottom of a crib, possessing spring elements to support the 75 sleeper in comfort.

Hinged to the outer or front of the end bars 10 is a leaf 12, which when shifted to a position at right angles to the bottom 9 constitutes one side wall of the crib and will be 80 held in such position by any suitable catch, such as 13. The provision of this element constitutes a safeguard against an infant rolling or falling from the crib and performs the further use or function next described when 85 the article is in use as a settee. The bottom 9, comprising a series of springs to constitute a spring crib-bottom, is liable to become distorted or misshapen when used as a settee. For sleeping purposes the article is particularly intended for a child's crib, and to afford a spring-rest the springs are necessarily relatively delicate. In these conditions when used as a settee, in which use it will ordinarily be occupied by adults of more considerable weight, the delicate springs of the crib-bottom are liable to become distorted and unfit for use as a crib-bottom. To protect this spring crib-bottom from such liability and preserve the springs thereof, the section 100 12, which constitutes one side wall of the crib, is hinged and so proportioned with relation to the width of the crib-bottom or seat foundation 9 that it may be folded over upon said bottom 9, and when so folded thereupon or thereagainst it will overlie or cover and protect the springs and serve as a base, as shown in Fig. 4, for the cushion 14. While so overlying, covering, and protecting the springs there is a space between the free edge 14^a thereof and the rear edge of the bottom 9 to permit the flap 15 of the cushion 14

to be folded over said edge 14^a and be confined between the section 5 and said bottom 9, whereby the cushion is held in place when the article is used as a settee. When it is desired to fold the article compactly for economy of space, the leaf 12 is folded upon the bottom 9, and said leaf and bottom are then folded alongside of or against the back 1 and the sections 5 and 6 folded inwardly against the bottom, as shown.

By my invention I provide an article of simple and economical construction and few parts, which may be easily manipulated and which will serve efficiently as a spring-bottom crib and also as a settee, in which latter use the spring-bottom of the crib is covered and protected by a section which also serves as one of the side walls of the crib or bed, and the elements of the article may be folded or nested compactly together for economy of space in shipment or for storage.

Having thus described my invention, what I claim as new, and desire to secure by Letters Patent, is—

1. A convertible article of furniture, consisting of a permanent, rigid frame which constitutes the back of the article when used as a settee, and one side wall thereof when used as a crib, a section pivoted at its inner end to said rigid frame and comprising springs to constitute a spring crib-bottom, and a leaf pivoted to the free end of said section, capable of being adjusted to a position at right angles therewith to constitute the other side

wall of the crib, and to be folded over upon said section to overlie, cover and protect the springs thereof, and end sections extending from said rigid frame constituting the arms of the article when used as a settee and the head and foot boards thereof when used as a crib.

2. A convertible article of furniture, consisting of a permanent, rigid frame which constitutes the back of the article when used as a settee and one side wall thereof when used as a crib, end posts for said back extending forwardly therefrom to provide a chamber or receptacle, end sections pivoted to said end posts, constituting the arms of the article when used as a settee and the head and foot board thereof when used as a crib, a bottom section pivoted at its inner end to said end posts and comprising springs to constitute a spring crib-bottom, and a leaf pivoted to the free end of said bottom-section, capable of being adjusted to a position at right angles therewith to constitute the other side wall of the crib and of being folded over upon said bottom-section to overlie, cover and protect the springs thereof.

In testimony whereof I have hereunto set my hand in the presence of two subscribing witnesses.

JOHN W. HUGHES.
